ABSTRACT

A ladies' clutch bag has an inverted U-shaped slit in its back wall providing an opening to receive material which forms the interior and inner wall of a coin purse, the outer wall of the coin purse being in common with that portion of the material of the back wall of the clutch bag which is below and within the confines of the slit. There are separable metal frame elements for the upper edges of the coin purse, the front one being connected to the upper margin of said last-mentioned common material, and the rear one being connected to the margin of a section of material at the inner side of the coin purse which can be flexed away from the wall of the clutch bag.

LADIES CLUTCH BAG WITH COIN PURSE

BACKGROUND OF THE INVENTION

1. Field of the Invention

The invention is useful in ladies' handbags and more particularly in ladies' clutch bags, but may be used in other similar items where it is desired to incorporate a small purse in the wall of a larger bag.

2. Description of the Prior Art

Heretofore it has been common to combine coin purses with clutch bags, but most constructions of this type involve merely a stitching or other securement of a coin purse to an external side or flap of a clutch bag. Typical of this type of construction is Kaufman U.S. Pat. No. 1,376,099. Rubin U.S. Pat. No. 2,745,456 discloses coin purses associated in different ways with the flap of a clutch bag. In no patents of which applicant is aware is the back wall of a clutch bag slit on an inverted U-shaped line to provide an opening for receiving material forming the coin purse, with the material of the back wall of the clutch bag which is below and within the confines of the slit also forming the front wall of the coin purse.

SUMMARY OF THE INVENTION

The present invention provides, in a ladies' clutch bag, a novel structural arrangement wherein a slit in the back wall of the clutch bag provides an opening for receiving material which is to form the liner and back wall of a coin purse, and wherein the material of the back wall of the clutch bag also forms the front wall of the coin purse.

A further object of the invention is to provide a clutch bag with an integral coin purse wherein novel structure is provided whereby the upper portion of the back wall of the coin purse can be moved away from the back wall of the clutch bag to facilitate manipulation of the clasp fasteners on metal frame elements.

A further object of the invention is to provide a ladies' clutch bag as above described wherein the lower portion of the coin purse is concealed thereby enhancing the appearance.

A further object of the invention is to provide a ladies' clutch bag wherein substantial portions of the coin purse are covered and thus protected from wear, and where only the metal trimmed edges of the coin purse are exposed to friction in use.

With the above and other objects in view the invention consists of the ladies' clutch bag with coin purse, and all of its parts and combinations, as set forth in the claims, and all equivalents thereof.

BRIEF DESCRIPTION OF THE DRAWING

In the accompanying drawing, in which the same reference numerals designate the same parts in all of the views:

FIG. 1 is a front elevational view of the clutch bag in closed condition;

FIG. 2 is a rear elevational view thereof showing the integral coin purse in closed condition;

FIG. 3 is a fragmentary sectional view taken approximately on the line 3-3 of FIG. 3 showing the coin purse in open condition;

FIG. 4 is a fragmentary view of the material for the back of the clutch bag before assembly, showing the generally crescent-shaped slit therein;

FIG. 5 is a perspective view of the material which forms the interior liner for the coin purse;

FIG. 6 is a plan view of the double-thickness material which is to be inset into the opening formed by the slit to provide the back portion of the coin purse;

FIG. 7 is a fragmentary plan view looking at the inner side of the material which is to form the back wall of the clutch bag, showing how the material of FIG. 6 is assembled therewith and secured thereto; and

FIG. 8 is a fragmentary sectional view taken on the line 8-8 of FIG. 7 but showing a further stage in the assembly.

DESCRIPTION OF THE PREFERRED EMBODIMENT

Referring now more particularly to the drawing, the clutch bag proper is generally of conventional form and includes a front wall 10 and a back wall 11, there being a back lining portion 11'. The lower edge of the back lining portion and the lower edge of the rear wall 11 are stitched to the front of a bottom gusset section 9. The upper edge of the back wall 11 and its lining are foldable over the top of the clutch bag to form the front flap 12, said flap having any suitable means such as the tab 13 for releasably securing the flap in closed position. In the structure of FIG. 1 there are coacting snap fasteners (not shown) on the inside of the lower portion of the tab 13 and on the wall 10. Except for the rear wall, the clutch bag proper is more or less conventional. The walls 10 and 11 and the gusset sections 9 are preferably formed of leather, but they may be formed of leatherlike plastic materials or of fabric. The lining 11' is usually formed of suitable cloth lining material.

Referring now more particularly to FIGS. 3, 4 and 5, the back wall 11 of the clutch bag has an inverted U-shaped slit, which in the preferred embodiment is a generally crescent-shaped slit 14 with downwardly curved ends so that the material 15 therebelow and bounded by the slit forms a flap which may be flexed outwardly to provide an opening for receiving the various sections of material which are to form the liner and back wall for the coin purse.

FIGS. 4, 5, 6 and 7 show various steps in the manufacture. Referring first to FIG. 6, a generally U-shaped piece of material 16 is provided which comprises an inner layer 17 and an outer layer 18. The upper edge of the inner layer 17 is cut to crescent shape as at 19 in the illustrated embodiment, to substantially conform to the shape of the slit 14, and the upper edge of the outer piece of material 18 is cut along a similar line 20 which is marginally spaced below the line 19 as shown in FIG. 6. The two layers of material 17 and 18 are stitched together by a generally crescent-shaped line of stitching 21 which is spaced below the margin 20 so that the material 22 of the layer 18, between the stitching and the margin, may be flexed outwardly in the manner shown in FIG. 8 to provide a V-shaped connection with the wall of the handbag above the slit. Preferably the two layers of material within and below the line of stitching 21 are glued together and provide a downward projection. The layers 17 and 18 are preferably formed of the same material as the outside of the clutch bag, so that if the bag is leather, the layers 17 and 18 are preferably leather.

The liner for the coin purse comprises a single piece of any suitable material 24 such as plastic, as shown in FIG. 5, which is doubled over on a fold line 24', the ends being stitched part-way together only partway up as at 25. This doubled liner is inserted and secured between the layer 18 and the wall portion 15 as shown in FIGS. 7 and 8 so that the upper edge of its front portion matches and conforms with the margin of the material 15 as at 26, and so that the upper margin of its rear matches and conforms with the upper margin of the piece 18 as at 27. Thus, referring to FIG. 8, the liner 24 of FIG. 5 provides a pocket-forming receptacle within the coin purse for receiving coins and other items, and the inset element 16 is located between the coin purse liner 24 and the clutch bag liner 11' as shown in FIG. 3.

Inverted U-shaped front and rear metal frame elements 28 and 29, respectively, each of which is inverted U-shaped in cross section, have central clasp projections 30 and 31. These are pivoted at their ends to each other as at 32 and 33, and the margins 26 and 27 of FIG. 8 are received in the U-shaped cross section, in the usual way, to finish said edges and form means for releasably closing the coin purse in the manner shown in FIGS. 2 and 3.

With this construction the back of the clutch bag is much neater in appearance than is the case where a coin purse is merely superimposed on a clutch bag. With the construction of the present invention the lower portion of the coin purse below the metal frame elements is completely concealed and protected from frictional wear. It is also to be noted that the leather, or other material 15 below the slit 14, forms both the

back wall of the clutch bag and the front wall of the coin purse, thus enhancing the overall appearance. The only exposed portions of the coin purse are protected by the metal frame elements 28 and 29.

By having the novel arrangement illustrated in FIG. 3, where the upper portion of the coin purse is swingable outwardly from the back of the clutch bag on the hinge point provided by the line of stitching 21, as shown in FIG. 3, it is possible to more conveniently operate the clasp fasteners 30 and 31 because the forefinger may then be inserted between the material 15 and the material 17. This arrangement is provided by the inset piece 16 which is of double thickness as shown in FIG. 6, with the upper portions of the layers separable as at 17-22 above the line of stitching 21 for the purpose above described. At the same time the rest of the material of the inset 16 is secured together as at 18 so that the inset piece forms a downward projection which, in reality, forms the inner wall of the coin purse, said wall also forming a partition between the receptacle 24 and the lining 11' of the clutch bag. By being of double thickness there is an effective reinforcing separation between the clutch bag proper and the coin receptacle 24 as is clear from FIG. 3. While the construction is particularly suitable for use in a clutch bag, it is obvious that the novel arrangement for incorporating a small purse in the wall of a larger bag has relatively wide application.

It is to be understood that I do not desire to be limited to the exact details of construction shown and described, for obvious modifications will occur to a person skilled in the art.

What I claim is:

1. In a handbag having a relatively flat upright wall portion, an inverted U-shaped slit in said wall portion having spaced lower ends whereby the portion of the wall within the slit provides a flap which may be flexed outwardly, a pocket-forming receptacle having inner and outer portions behind said flap, the outer portion of said receptacle having an upper margin substantially matching the upper marginal edge of the flap and secured thereto, inner connecting means connecting the inner portion of the receptacle to the lower marginal edge of the material of said handbag wall which is above said slit, a metal frame connecting the upper margin of the outer portion of the receptacle to the upper margin of the flap, a metal frame hinged to the first frame and connecting the upper margin of the inner portion of the receptacle to said inner connecting means, and means for detachably closing said hinged metal frame members.

2. A handbag as defined in claim 1 in which said inner connecting means is V-shaped in cross section and has separable inner and outer sections.

3. In a handbag having a relatively flat, upright wall portion,

a slit in said wall portion whereby a flexing portion of the wall below the slit may be flexed outwardly, a pocket-forming receptacle having inner and outer portions positioned behind said flexing wall portion, the outer portion of said receptacle having an upper margin secured to said flexing wall portion below the slit, inset means which is V-shaped in cross section and which has separable inner and outer sections, the inner section of said inset means having an upper margin secured to the marginal edge of the material of the handbag above said slit, and the outer section of said inset means having its upper marginal edge secured to the inner portion of the receptacle.

4. In a handbag having a relatively flat, upright wall portion, an inverted U-shaped slit in said wall portion having spaced lower ends whereby the portion of the wall within the slit provides a flap which may be flexed outwardly, a pocket-forming receptacle having inner and outer portions positioned behind said flap, the outer portion of said receptacle having an upper margin substantially matching the upper marginal edge of the flap and secured thereto, and means for detachably closing said flap and receptacle, there being means connecting the inner portion of the receptacle to the lower marginal edge of the material of said handbag wall which is above the slit and including inset means which is V-shaped in cross section and which has separable inner and outer sections, the inner section having an upper margin secured to the marginal edge of the material of the handbag above the slit, and the outer section having an upper marginal edge secured to the upper marginal edge of the receptacle.

5. A handbag as claimed in claim 4 in which the upper margin of the inner section of the inset material substantially matches the slit in shape.

6. A handbag as claimed in claim 4 in which there is a metal frame connecting the upper margin of the outer portion of the receptacle to the upper margin of the flap, and a metal frame hinged to the first frame and connecting the upper margin of the inner portion of the receptacle to the outer section of the V-shaped connecting means.

7. A handbag as claimed in claim 6 in which the means for detachably closing the flap and receptacle comprises clasps on the metal frame members.

8. A handbag as claimed in claim 4 in which the inset means connecting the inner portion of the receptacle to the handbag has a downward projection positioned inwardly of the receptacle.

9. A handbag as claimed in claim 8 in which the handbag has a lining and in which the downward projection of the inset forms a partition between the receptacle and the handbag lining.
